SASH CONSTRUCTION

Jacob Fuchsman, Brooklyn, N. Y.

Application June 29, 1935, Serial No. 29,048

1 Claim. (Cl. 20—50)

This invention relates to sash constructions and in particular to an arrangement of sash parts which will facilitate the inward opening of the windows for the purpose of cleaning or the like.

A particular object of my invention is to provide a construction which will embody a movable strip member which can be readily operated by the housewife to release the sashes preparatory to swinging the same inwardly, the operation of the strips requiring a minimum of effort and practically no skill.

A still further and important object of my invention is to provide a hinging means in connection with the sashes which includes a weather strip for sealing the sashes against the action of the elements and which at the same time permits the sashes to be raised and lowered as any ordinary window.

A still further object of my invention is to provide a sash construction which will make use of sash weights at one side only necessary, will be adaptable to sash frames in use, will be inexpensive to install and will be easily and quickly operable to swing the sashes inwardly for any purpose desired.

Changes and variations may be made in the construction shown and described without departing from the principles of the invention or sacrificing its chief advantages; hence such invention is not to be confined to the precise structure shown in the drawing, in which;

Figure 1 is a sectional plan view of the construction contemplated by my invention and showing arrangement of the sash strips and hinge members employed, the open position of the sashes being indicated by the outline position.

Figure 2 is a front view in elevation of the lower sash, parts being broken away to illustrate the construction, and

Figure 3 is a fragmentary view in plan section illustrating how one side of the sash frame will be shaped when my improvement is built into new sash frame constructions.

Referring to the drawing in detail, 5 indicates a sash frame, having the usual side channels or grooves 19 in which ride the sashes, the upper sash being indicated by the numeral 6, and the lower sash by numeral 7. At the left side only, the sash frame is provided with the wells for the reception of the sash weights 8 which are attached in the usual manner to the sashes by the cords or chains 9. The sash frame includes the usual outer strip 10, the center strip 11 and inner strip 12, between which strips the sashes 6 and 7 may have vertical sliding movement.

In order to adapt the outer or upper sash 6 to have inward swinging movement, I secure in any suitable manner, a weather strip 13 to the center strip 11 so that the curled end or edge 14 of the weather strip 13 is in position to receive the turned over end 18 of a hinge plate forming part of a hinge 17 that is secured to the sash 6 adjacent the upper and lower edges of said sash. As many of these hinges may be employed as desired.

As shown, the hinges are preferably at the right side of the sash, but may be placed at the left side if desired. At the left side, as illustrated, the sash 6 is provided with an edge strip 20, mounted thereon for movement toward and away from the edge of the strip by screw and slot connections, the screws being indicated as at 24 and the slots as at 25. In order that the edge strip 20 may be moved toward and away from the edge of the sash, use is made of a finger lever 21 which is riveted as at 23 to the strip 20 and has pivoted thereto the screw 22 secured in the sash 6. The strip 20 is permitted to operate by the slots 25, and when it is desired to open the sash the lever 21 is thrown to the position shown in outline in Figure 1 and the strip 20 is moved to retracted position as shown in outline. The retractile movement of the strip 20, which has extended in behind the center strip 11 of the sash frame construction releases the sash 6 and allows it to be swung inwardly. This strip 20 is also a weather strip and effectively seals the window against the elements.

The outer sash will clear the center sash strip 11 in its swinging movement, as will also the inner sash 7 whose edge carries a like strip 20 and lever 21. The strip 20 on the inner sash 7 moves in behind the inner sash strip 12 and also effectively seals the inner sash. Both strips 20 act as weather strips. The inner sash is mounted for inward swinging movement in practically the same manner as is the upper sash 6, the weather strip 15 being secured to the sash frame 5 beneath the inner strip 12 so that the slot forming bend 16 in the edge of the strip 15 is closer to the sash frame and gives the lower sash a shorter arc to swing through thus permitting both sashes to be opened a maximum amount. The turned over end 18 of the hinges 17 secured to the inner sash is slideable in the weather strip 15 and the sash can operate freely in vertical direction and can be swung inwardly at any point in its vertical movement so that the housewife in cleaning the outer surfaces of the windows can pull the sashes down or raise them to any convenient height. The hinges are preferably secured to the inner sash 55

adjacent the upper and lower edges thereof, and as many as desired may be used.

In the form of my invention illustrated in Figure 3, the sash frame has been originally made to accommodate the sash construction already described and in order to permit the sashes to swing inwardly, the sash frame is provided with the stepped sash runways 29 and 30 each having slots therein for the reception of the sash strips 31 which are identical, in all respects to the strips 28 described. The outer bead 26 of the frame, as well as the strips 31 prevent any outward movement of the sashes and the strips 31 are also weather strips and are retractible to permit inward swinging of the sashes.

It is evident therefore that I have provided a sash construction which can be quickly installed with a minimum of alteration to the existing sash frame, one which is easy to operate and one 20 which is swingable completely into a room so that danger of cleaning the windows from the outside is eliminated. The weather strips extend the length of the sash frame opening.

My invention is not to be restricted to the precise details of construction shown since various changes and modifications may be made therein without departing from the scope of the invention or sacrificing its chief advantages.

What I claim is:

30 In a sash construction, in combination, a sash frame, an upper outer sash, an inner lower sash, inner, outer and central sash strips on opposite

sides of the frame defining grooves in which the sashes are disposed for vertical sliding movement, weather strips, an outer one of which is mounted on the face of said central sash strip and an inner one on the sash frame beneath said inner sash strip, said weather strips extending the length of said sash strips and each having a curled edge, spaced hinges including hinge plates secured adjacent the upper and lower corners of one side of each of said sashes, one of the hinge plates of each hinge having a turned over hook portion for interfitting relation with the curled edge portions of said weather strips whereby said hinge plates can slide vertically in the weather strips when the sashes are raised and lowered, the curled portion of the inner weather strip being closer to the sash frame than the curled edge portion of the outer weather strip whereby the lower inner sash swings closer to the sash frame than the upper sash so that maximum swinging movement of both sashes is provided, slide strips constituting weather strips at the opposite edges of the sashes from said hinges for engagement with said inner and central strips, pin and slot means for attaching said slide strips to the sashes and a lever on each slide strip for moving said slide strips out of contact with the sash strips whereby said sashes can be swung inwardly on their hinges at any vertical position in the sash frame.

JACOB FUCHSMAN.
